BED.

No. 824,068.

Specification of Letters Patent.

Patented June 19, 1906.

Application filed September 11, 1905. Serial No. 277,924.

To all whom it may concern:

Be it known that I, JASPER L. DODGE, a citizen of the United States, residing at Providence, in the county of Providence and State of Rhode Island, have invented a new and useful Improvement in Beds, of which the following is a specification.

This invention has reference to an improvement in beds, and more particularly to an improvement in means for detachably securing the bed-bottom to the frame of the bed.

The object of my invention is to improve the construction of beds or bedsteads whereby the elastic bottom of the bed may be quickly secured to the bed-frame under tension and readily detached from the bed-frame, when it may be rolled up for carrying or packing purposes.

My invention consists in the peculiar and novel construction of a bed consisting of a bed-frame, brackets secured to the bed-frame, an elastic bed-bottom, means on the brackets and the bed-bottom for securing the bed-bottom to the brackets, and means for stretching the bed-bottom over the brackets, with details of construction, as will be more fully set forth hereinafter.

Figure 1 is a side view of my improved bed, showing the elastic bed-bottom secured to the brackets on the side rails of the bed-frame and the means for stretching the bed-bottom over the brackets. Fig. 2 is a detail sectional plan view taken on line X X of Fig. 1, showing the means for securing the bed-bottom to the brackets. Fig. 3 is an enlarged detail view looking at the inner face of one of the brackets, showing the means for securing the bracket to the side rail of the bed-frame and the means for securing the bed-bottom to the bracket, and Fig. 4 is an enlarged perspective view of the tool used for stretching the bed-bottom over the brackets.

In the drawings, *a* indicates the headboard; *b*, the footboard; *c c*, the side rails; *d d*, the brackets; *e*, the bed-bottom of my improved bed, and *f*, the tool used for stretching the bed-bottom *e* over the brackets *d d*. The brackets *d d* each have the hook-shaped upper end *d'* and the hole *d''* adjacent the hook-shaped end. These brackets are shaped to extend above the side rails *c c* and are secured to the side rails at the head and foot of

the bed by the screws *d'' d''*, as shown in Figs. 1 and 3. The bed-bottom *e* consists in the preferred form of a plurality of coiled springs interlaced or woven together and secured at their ends (in any well-known way) to the bars *e' e'* in the ends of which are the holes *e'' e''*, as shown in Fig. 2. These holes *e'' e''* are shaped to receive the hook-shaped upper ends *d' d'* of the brackets and the end of the stretching-tool *f*, which has the offset-pin *f'*, adapted to enter a hole *d''* in a bracket and form a pivot or fulcrum for the tool.

The bed-bottom *e* is quickly secured to the brackets *d d* by placing one of the bars *e'* over the brackets at the head of the bed, with the hook-shaped upper ends *d' d'* of the brackets extending through the holes *e'' e''* in the bar, as shown in Figs. 2 and 3. The end of the tool *f*, having the pin *f'*, is now inserted in succession through the holes *e'' e''* of the bar *e'* at the foot of the bed and the pin *f'* on the tool inserted in the hole *d''* in the bracket, bringing the tool *f* into the position as shown in broken lines in Fig. 1. The tool *f* is now forced over toward the footboard *b* into the position shown in full lines in Fig. 1 and, acting as a lever on the bar *e'*, stretches the bed-bottom and draws the bar over the brackets into a position for the hook-shaped end of the brackets to enter the holes in the bar. The tool *f* is now removed, leaving the bed-bottom firmly secured to the brackets under the required tension. The bed-bottom may be readily removed from the brackets by reversing these operations and left flat or rolled up into a comparatively small package for carrying or packing purposes.

It is evident that the bed-bottom proper may be constructed of any elastic fabric—such as wire springs, canvas, or webbing—and secured to the end bars *e' e'* without materially affecting the spirit of my invention.

Having thus described my invention, I claim as new and desire to secure by Letters Patent—

In combination with the side rails of a bed, a bracket secured adjacent each end of each rail and each embodying a hook-shaped upper end with an aperture disposed to the rear of said upper end and below the same, an elastic bed-bottom having bars attached to its ends with elongated apertures formed ad-

jacent the ends of the bars and being of greater length than the width of said hook-shaped bracket ends, to permit a wrench to be received in said elongated apertures and 5 to engage in the bracket-aperture to enable said bars to become engaged over said hook-shaped ends.

In testimony whereof I have signed my name to this specification in the presence of two subscribing witnesses.

JASPER L. DODGE.
